(No Model.)

K. C. GILLETTE.

COMBINED FAUCET AND TAP VALVE.

No. 294,610.

Patented Mar. 4, 1884.

UNITED STATES PATENT OFFICE.

KING C. GILLETTE, OF NEW YORK, N. Y., ASSIGNOR TO JOSEPH L. SPOFFORD, OF SAME PLACE.

COMBINED FAUCET AND TAP VALVE.

SPECIFICATION forming part of Letters Patent No. 294,610, dated March 4, 1884.

Application filed September 13, 1883. (No model.)

To all whom it may concern:

Be it known that I, KING C. GILLETTE, a citizen of the United States, and a resident of New York, in the county and State of New York, have invented certain new and useful Improvements in Combined Faucet and Tap Valve, of which the following is a specification, reference being had to the drawings accompanying and forming a part of the same.

10 My invention involves an improvement in combined faucet and tap valves for use generally in drawing off the contents of casks, kegs, and other vessels, but more particularly designed for use with receptacles containing ale, beer, and other malt liquors, or such as are under pressure from fermentation or effervescence.

Heretofore appliances of various kinds have been employed for plugging or closing the tap-holes of casks or kegs of this kind; but no means, so far as I am aware, have been devised for completely obviating certain difficulties that are encountered in their use. The usual and best known method of closing the tap-holes has hitherto been to drive in a simple wood or cork plug, which is driven into the cask by the insertion of the faucet. This plan, particularly in the case of malt liquors, is objectionable, from the difficulty of extracting the plugs on refilling the casks, and for the reason that the insertion of the faucet by means of a mallet agitates the liquor and liberates the gas.

With a view to obviating the objections which the ordinary taps present, appliances have been devised for insertion in the bung-holes in barrels and casks which consist, mainly, of a cup or socket containing a valve arranged to be opened by the insertion and closed by the withdrawal of the faucet or cock. Over devices of this class my present invention is an improvement, the general nature of the invention being as follows: I employ a screw-threaded cup or bushing, which is inserted in the bung or tap hole of the cask. This cup contains a valve provided with inclined flanges or screw-threads that engage with threads or lugs within the cup, and which, when turned, is moved toward or from the bottom of the cup. To effect this movement, I provide the valve with suitable pro-

jections, which register with corresponding notches in the faucet when the latter is inserted, and I take advantage of this movement for opening and closing communication 55 with the interior of the cask and for holding the faucet in its place.

The construction in detail of the devices which I employ for this purpose will be described by reference to the accompanying 60 drawings, where—

Figure 1 is a central longitudinal section of my invention, showing the manner of its application to a cask. Fig. 2 is a similar section of a portion of the device with the valve 65 in another position; Fig. 3, a top view of the cup or bushing for containing the valve; Fig. 4, a section of the same. Figs. 5 and 6 are top and vertical sectional views, respectively, 70 of the face-plate; Fig. 7, a top view of a modified form of valve; Fig. 8, a side elevation of the same, showing a portion of the cup or bushing in section. Fig. 9 is a top view of the valve with slight modifications; Fig. 10, a side elevation of the same.

75 Similar letters of reference indicate corresponding parts in all the figures.

The letter A designates a portion of the head of a cask or keg, provided with the usual tap-hole for drawing off its contents. In the tap-hole, which is screw-threaded, is inserted a cup or shell, B, of metal, screw-threaded on its exterior. In the bottom of the cup B are a number of perforations, a. Its rim b is flanged and provided with a groove, c, portions being 80 cut away at two or more points, c', as shown in Fig. 3.

C is an annular flanged face-plate provided with the lugs or ears d', that register with the cut-away portions c' and permit the plate to 85 be applied to the cup B and held in place when the plate is turned to bring the lugs into the grooves c.

In the bottom of the cup B is placed a metal cup, D, on the sides of which are two inclined flanges, d d', constituting right and left hand screw-threads. At diametrically opposite points on the interior of the cup B are lugs e e', or any equivalent means that afford guides or bearing-surfaces for the threads on the valve 95 D, and cause the same to be raised or lowered 100 within the cup B when turned in one direc-

tion or the other. The valve D is of smaller diameter than the cup B. A space is therefore left between it and the sides of the cup.

E is a ring or washer of soft rubber, which is placed in the forward part of the cup B.

F is a metal ring, placed against the washer, and nearly or quite filling the space between the washer and the rim of the valve D.

In the bottom of the cup B, and around the perforations, is set a rubber washer, f, forming a seat for the valve D. The latter is provided with two or more lugs or projections, gg.

G is an ordinary faucet having a straight shank, H, of a diameter nearly equal to that of the opening in the annular face-plate C. A groove, h, is formed in the shank, and slots or notches K K are cut in the end in position to register with the lugs gg on the valve D.

The manner of applying and using the device is as follows: The valve D, ring F, the washer E, and plate C having been placed in the relative positions above described, the faucet is inserted through the plate C until the lugs gg enter the slots in its end. The faucet is then turned bodily, say one-quarter of a revolution, by which the valve D is raised away from its seat, opening communication between the interior of the cask and the faucet. This movement brings the rim of the valve D against the ring F with great force, compresses the washer E, and causes it to enter the groove h in the faucet. This condition of the parts is shown in Fig. 2. While the valve D is raised, therefore, the faucet is held firmly in place, this having been effected without disturbing the contents of the cask, which may then be drawn off in the usual way. To remove the faucet, it is turned back one-quarter of a turn, which brings the valve D back firmly on its seat and closes the cask. The washer E at the same time resumes its original shape and permits the faucet to be withdrawn without opposition.

Though the construction of the parts which I have now described may be considerably varied and modified, I will describe in detail only such modifications as I regard as best calculated to reduce the cost and simplify the construction of the device.

50 In lieu of using a valve with solid bottom, I may use one with a number of perforations, (such as shown in Fig. 7,) in which case the

bottom of the cup B will contain but one central opening, n, Fig. 8, and a washer, m, be attached to the bottom of the valve D.

The valve D, in lieu of being in the form of a cylinder, may be a plate, N, Figs. 9 and 10, with the inclined sides pp, carrying the threads or ways dd' and ending in the lugs or ears gg.

Without limiting myself to the precise details shown, what I now claim as my invention is—

1. The combination, with a faucet having notches in its end, of a cup or shell with a perforated bottom, a valve with inclined ways engaging with guides in the interior of the cup or shell, and provided with lugs for engaging with the notches in the faucet, and an elastic ring or washer confined within the cup and adapted to be compressed around the faucet by the forward movement of the valve, substantially as set forth.

2. A tap-valve consisting of a threaded cup with perforated bottom, a removable annular face-plate and elastic ring or washer, and a screw-threaded valve provided with lugs or ears, in combination with a faucet of a conformation to be inserted through the face-plate and elastic ring, and having notches in its end for engaging with the lugs or ears on the valve, whereby the latter may be turned and raised, substantially as set forth.

3. The combination, with a cup or shell having a perforated bottom, of the removable annular plate C, the elastic ring F, washer E, screw-threaded valve D, having lugs gg, and a faucet provided with notches or slots for engaging with and operating the valve in the manner set forth.

4. The combination, with the shell or cup B, having a perforated bottom, of an annular face-plate, C, an elastic ring or washer confined thereby, a plate or valve having lugs gg, and inclined flanges or threads engaging with guides in the cup, and a faucet having a cylindrical shank provided with a groove, h, and slots K K, all substantially as herein described.

In testimony whereof I have hereunto set my hand this 7th day of September, 1883.

KING C. GILLETTE.

Witnesses:
